UNITED STATES PATENT OFFICE.

OTIS R. ANGELL, OF HAVERHILL, MASSACHUSETTS, ASSIGNOR TO HAMEL SHOE MACHINERY COMPANY, A CORPORATION OF MASSACHUSETTS.

EDGE SETTING AND BURNISHING MACHINE.

1,392,903.

Specification of Letters Patent. Patented Oct. 11, 1921.

Application filed March 30, 1918. Serial No. 225,672.

To all whom it may concern:

Be it known that I, OTIS R. ANGELL, a citizen of the United States, residing at Haverhill, in the county of Essex and State 5 of Massachusetts, have invented certain new and useful Improvements in Edge Setting and Burnishing Machines, of which the following is a specification, reference being had therein to the accompanying drawings.

10 This invention relates to edge setting and burnishing machines of that type in which a vibratory tool-supporting rocker arm is employed, and more specifically to that form of machine wherein a tool holder adapted to 15 carry a pair of tools is rotatably mounted upon the rocker arm, rotation of said tool holder serving to place said tools alternately in operative position for acting upon the shank and forepart respectively of the shoe 20 sole.

The present invention resides in the provision of means for mounting and vibrating said rocker arm whereby the latter may be made more compact in form than in types of 25 machines at present in commercial use, thereby greatly decreasing objectionable vibration of surrounding parts, while at the same time lowering the cost of manufacture and upkeep of the same.

30 The invention further consists in novel means for rotatably mounting the tool holder with respect to the rocker arm and for locking said tool holder in either of two operative positions.

35 The invention further consists in the provision of means, conveniently located for manipulation by the operator, for unlocking said tool holder to permit the same to be turned.

40 A valuable feature of the invention resides in novel means for turning said tool holder to a new operative position, after the same is unlocked, such means being arranged to act subsequently to the unlocking 45 operation, without necessitating further, positive action on the part of the operator.

The invention further resides in the provision of a single manually slidable element carried in the tool-supporting member 50 whereby the operator, by a simple pressure of his hand, may both unlock and cause rotation of the tool holder to another operative position.

Other and further objects and advantages 55 of the invention together with improved de-

tails of construction and desirable combinations of parts will be hereinafter described at length and more particularly pointed out in the claims, reference being had to the accompanying drawings in which, —

60 Figure 1 is a side elevation, partly in section, of so much of the upper portion of the frame of an edge setting machine of usual form as is necessary to show the application of the present invention thereto,

65 Fig. 2 is a view, from the right hand side of Fig. 1, showing the tool-carrying and operating parts in elevation, the frame being omitted.

Fig. 3 is a vertical transverse section of 70 the parts shown in Fig. 2,

Fig. 4 is a vertical section through the parts shown in Fig. 2 taken on the line 4—4, Fig. 3,

75 Fig. 5 is a detail of the manually operable slide member, and

Fig. 6 is a bottom plan view of a portion of the tool-supporting arm showing a detail of the locking mechanism.

80 Referring to the drawings, numeral 1 indicates the upper portion of a pedestal or frame member which may be of any usual or well known construction such as is commonly employed in machines of this type. This frame member is provided at its upper 85 portion with aligned bearing members 2—2', providing journal bearings for a driven shaft 3, (Fig. 3), said shaft having fixed thereto between the bearings 2—2' a drive pulley 4, which may be rotated from any 90 suitable source of power. The bearings 2—2' are herein shown as provided at 5—5 with oil cups whereby the driven shaft may be properly lubricated.

95 6 indicates a bracket member serving to support, at its free extremity, a finger hook of usual construction, the upper portion of which is as indicated at 7, the bracket 6 also providing for suitably holding the gas pipe 8 leading to a burner, not shown, for heating the tools. As herein illustrated, the bearing member 2' has formed in its outer end, and closely adjacent the journal opening of the shaft 3, a cylindrical cavity 9, in which is fixed, as by means of a set screw 11, 100 a pintle pin 10, said pin being provided at its outer extremity with an enlarged head 12. 105 13 is a tool-supporting member or rocker arm, having an enlarged head portion 14, and a tail portion 15 of substantially cylind-

cylinder moving in the fluid thereof and engaging the adjacent end of the respective piston.

2. A drive shaft in axially alined sections, disks secured to the adjacent ends of said sections, arcuate fluid holding cylinders carried by one of said disks and circumferentially spaced thereon in pairs, double end plungers carried by the other disk and projecting between the cylinders of the pairs, the ends of each plunger extending into the adjacent ends of the cylinders of each pair and slidale therein in spaced relation to the walls of the cylinders, said cylinders being partially filled with fluid, and springs within the cylinders moving in the fluid and engaging the extremities of the plungers as described.

3. A drive shaft in axially alined sections, disks secured to the adjacent ends of said sections in spaced apart relation, arcuate fluid holding cylinders carried by one of said disks and circumferentially spaced in pairs, double end plungers outstanding from the other disk having oppositely projecting end portions paralleling the disk and forming pistons within the inner ends of the cylinders of said pairs of cylinders, spaced from the walls of the cylinders, said cylinders being partially filled with fluid, and springs operating in the fluid within the cylinders and engaging the extremities of said pistons for the purpose described.

In testimony whereof I have affixed my signature.

ERNIE ADAMSON.

44 is a transverse opening formed in the rocker arm 13 adjacent the upper end of the bore 31, and serving to guide a slide member 45, said member being provided at 5 its forward extremity, which projects beyond the face of the rocker arm 13, with a knob 46, said knob being engageable by the hand of the operator for a purpose which will be hereinafter described. Fixed upon 10 the rear extremity of said member 45 is a washer 47 of a diameter sufficient to overlap the edges of the opening 44, said washer being held in fixed position upon the slide 45 by means of a screw 48 or other suitable 15 device, a collar 51 being interposed between the head of said screw and the washer.

Within the bearing member 2' and adjacent the opening 9 is an opening 49, such opening providing a pocket for a compression spring 50, this spring bearing at one 20 end against the bottom of said pocket and having its other end encircling the collar 51 and bearing against the washer 47. The spring 50 tends to maintain the slide member 25 45 in extreme forward position, the washer 47 serving to prevent said member 45 from being forced entirely out of the opening 44. In the slide member 45 is formed a narrow slot 52 adapted for engagement by the flattened portion 43 of the 30 disengaging pin 42, the latter thus serving to prevent rotation of member 45 about its own axis. The upper wall of said slot 52 constitutes a cam surface 53, said surface 35 inclining downwardly and forwardly from its rear end, the forward portion, however, being straight and substantially parallel with the axis of the opening 44. It will be now evident that movement of the slide 40 member 45 rearwardly against the action of the spring 50 will cause a downward movement of the disengaging pin 42 by reason of the engagement of the same with the cam element 53, whereby after sufficient 45 movement of the slide member 45, said disengaging pin will force the locking pin 38, then projecting into the opening 41, out of operative engagement with the same, thereby permitting the tool holder 28 to be 50 freely rotated about the pintle pin 32. In order to prevent projection of pin 42 into locking engagement with one of openings 37', the inclined portion of cam 53 has just sufficient throw to move the lower extremity 55 of said pin to a position flush with surface 33, the straight portion of the cam serving to permit additional movement of the slide member 45 after the disengagement of the locking pin without further moving the disengaging pin 42.

As herein shown, the pintle pin 32 is provided upon its upper extremity with one element 54 of a ratchet clutch, the co-operating element of such clutch being shown at 60 56. 55 indicates teeth carried by the re-

spective elements, said teeth being formed with straight portions 55^a, and inclined portions 55^b, the first of which, upon rotation of one of said clutch elements in one direction, serve to positively drive the other of 70 said clutch elements, while the second, upon rotation of the first element in the opposite direction act as cams to separate the clutch elements, thereby preventing any driving transmission between the same. 75

The clutch element 56 is herein shown as slidably guided for movement toward and from the clutch element 54 by the side walls of opening 31 and also by means of a guide pin 57 slideable within a suitable opening in 80 the pintle pin 32, said clutch element 56 having fixed thereto an elongated gear 58. 59 is a light compression spring bearing upon the bottom of the cavity 31 and serving to normally hold the clutch elements 85 54 and 56 in operative engagement but permitting the same to be separated as above indicated. Upon the slide member 45, adjacent the gear 58, is formed a rack 60 meshing with said gear 58, sliding movement of the member 45 thus serving to rotate the gear 58. 90

By reason of the above described construction it will be evident that upon movement of rod 45 inwardly, the gear 58 will 95 be rotated, as herein shown, in a left hand direction. Such movement of the gear 58 together with the clutch element 56 serves to cause the inclined portions 55^b of the teeth 55 carried by part 56 to ride up on the corresponding inclined portions of the teeth of clutch element 54, thus serving to move the gear 58 against the tension of the spring 59, causing the separation of the clutch elements. Rotation of gear 58, as above indicated, therefore fails to impart any rotation to the pintle pin 32 and tool holder 28. Upon release of the knob 46 by the hand of the operator the spring 50 in expanding will reciprocate the slide 45 in the opposite direction, thus turning the gear 58 in a right hand direction, the vertical elements 55^a of the clutch teeth 55 now engaging each other, and serving to positively drive the pintle pin 32 and tool holder 28, to cause a rotation of the latter. 110 115

The operation of the machine may now be briefly stated as follows:

Upon rotation of the drive shaft 3 the crank arm 25 through the connecting rod 120 and wrist pin 27 acts to rapidly vibrate the rocker arm 13 about the pintle pin 10. The tool holder being in the position herein shown, and it being assumed that the tool shown at the right of Fig. 1 has been in 125 use, and it being desired to reverse the tool holder whereby to present the other tool in operative position, the operator will press on the knob 46 thereby moving the slide member 45 against the tension of spring 50. 130

During the first portion of such movement, disengaging pin 42, acted on by cam 53, will move downwardly in its guide opening, pressing down upon the extremity of the locking pin 38 until the latter has been moved out of engagement with the opening 41 of the rocker arm, thus releasing the tool holder for operation. During this movement of the slide member 45 and while the locking pin 38 was still in engagement with the opening in the rocker arm, the rack 60 has been rotating the gear 58, but as above pointed out, by reason of inclined faces of the clutch teeth 55, such rotation of the gear 58 serves merely to separate the normally engaging clutch elements 54, 56, thus permitting a free turning movement of gear 58, and inward movement of the slide member 45, but without imparting any rotational movement to the tool holder 28. Upon release of the knob 46 by the operator the spring 50, which has been compressed during the above operation, will immediately expand, pushing the slide member 45 forwardly, the clutch element 56 now positively engaging the clutch element 54 to turn the latter through a half revolution. During the first portion of the movement of the slide member 45, the disengaging pin 42 is held down in extreme position, but when said pin is permitted to rise by engagement with the inclined portion of cam 53, the extremity of the opening 41 is left free for engagement by the locking pins 38. By reason, however, of the fact that the tool holder has at this time already received a slight turning movement, the previously active locking pin has been brought out of alignment with opening 41, the locking pins at this time being all held downwardly within the tool holder 28 by engagement of their upper extremities with the surface 33 of the rocker arm. When upon the continued rotation of the tool holder 28, a locking pin is presented beneath the opening 41, said locking pin immediately snaps upward into said opening thereby locking the tool holder in its new position. As the rotation of the tool holder from one position to another is rapid, it has been found in practice that at times the locking pin will be carried past said opening, thus failing to properly lock the tool holder in desired position, and in order to avoid such action the surface 33 of the rocker arm, in advance of the opening 41, has been provided with an inclined groove 61 leading into said opening 41, said groove serving to permit a slight outward movement of the locking pin just prior to engagement of the same with the opening 41, thereby insuring proper engagement of said pin therewith.

While as above pointed out the present structure has been shown as devised for the employment of two diametrically opposed

tools, it is clearly evident that by slight and obvious modifications in the structure a greater or lesser number of tools might be employed if this were found desirable. Furthermore, while the machine as herein illustrated is provided with a tool operating mechanism at one side, only, of the frame, it is to be understood to be within the scope of the present invention to apply a similar mechanism to the opposite side of the frame and to actuate it from the same drive shaft if desired.

Having now described the mechanism in its preferred form, together with details of construction and the mode of operation of the same, what I claim and desire to secure by Letters Patent of the United States is,—

1. In an edge setting machine, in combination, a bearing member, a drive shaft journaled therein, a crank upon said shaft, a rocker arm pivoted upon said bearing member closely adjacent said crank and arranged to swing in a plane at right angles to said shaft, a wrist pin fixed to said rocker arm and a connecting rod constructed to transmit motion from said crank to said wrist pin to thereby vibrate said rocker arm.

2. In an edge setting machine, in combination, a frame providing a bearing member, a driven shaft journaled in said bearing member and projecting beyond the end of the same, a crank upon the projecting end of said shaft, a rocker arm, means for pivotally supporting said arm to turn about an axis closely adjacent the axis of the shaft, a wrist pin carried by said rocker arm and a connecting rod for connecting said crank and wrist pin whereby rotation of the shaft acts to vibrate said rocker arm about its pivot.

3. In an edge setting machine, in combination, a frame member, a tool-supporting rocker arm pivoted to said member to vibrate with respect thereto, said rocker arm being provided with an internal cavity, and means comprising a pivoted connecting rod located within said cavity for vibrating said arm.

4. A vibratory rocker arm for edge setting machines comprising a tool-supporting tail portion and an enlarged head portion, said head portion being provided with a journal opening, with an internal cavity communicating with said opening, and with a wrist pin in said cavity.

5. In an edge setting machine, in combination, a tool-supporting rocker arm comprising a head or casing provided with a cavity therein, journal means constructed and arranged to permit vibrating movement of said rocker arm, means including a connecting rod located within said cavity for vibrating said rocker arm, and a tool-carrying member mounted upon said rocker arm.

6. In an edge setting machine, in combination, a vibratory rocker arm, a tool holder rotatably mounted upon said rocker arm, a movable clutch element carried by 5 one of said parts and arranged to engage said other part to prevent relative rotational movement of said parts and clutch disengaging means carried by said latter part.

7. In an edge setting machine, a vibratory tool-supporting member, a tool holder rotatably mounted therein and means for normally locking said parts against relative rotation comprising a spring pressed latch 10 slidably carried by said tool holder and arranged to engage a coöperating element upon 15 the vibratory member.

8. In an edge setting machine, a supporting member a rotatable tool holder mounted thereon, a locking pin in said tool holder 20 arranged for engagement with said member to hold said parts against relative rotation, a disengaging element movable with respect to said member for rendering said pin inoperative, and manually operable means for 25 actuating said element.

9. In an edge setting machine, in combination, a rocker arm, a tool holder journaled to turn thereon, the opposed surfaces of said arm and holder being provided with alined 30 openings, a spring pressed pin slidable within one of said openings and arranged normally to project into engagement with said other opening whereby to lock said arm and holder against relative rotation, and 35 manually operable means, independent of said pin, for disengaging the pin from said latter opening.

10. In an edge setting machine, in combination, a tool-supporting member, a tool holder 40 mounted for rotation thereon, the opposed surfaces of said parts being provided with alined openings, a spring pressed latch pin slidable in the opening of said holder and arranged to be normally projected into locking 45 engagement with the opening in said member, and an element slidable in said latter opening for disengaging said latch pin therefrom.

11. In an edge setting machine, in combination, a rocker arm, a tool holder rotatably mounted thereon, latch means for locking said parts against relative rotation and a manually operable cam element carried by 50 said rocker arm for rendering said latch means inoperative.

12. In an edge setting machine having a 55 vibrating rocker arm and a tool holder rotatable thereon, in combination, means for locking said holder against rotation comprising a spring-pressed pin carried thereby and arranged to engage an opening in said arm, a disengaging pin slidable in said opening, and a member slidably guided for movement in said arm and provided with a 60 cam element for actuating said disengaging

pin, whereby operation of said member serves to unlock said holder to permit rotation thereof.

13. In an edge setting machine, in combination, a rocker arm having a journal 70 opening therein, a tool holder provided with a pintle pin supported to turn in said opening, a plurality of spaced apart, spring-pressed locking pins in said holder arranged for successive engagement with an opening 75 in said arm, and means carried by said arm for disengaging said pins from said opening.

14. In an edge setting machine, in combination, a rotatable tool holder, means for locking the same against rotation, and 80 means for unlocking and rotating said tool holder, said means comprising a hand operated element movable in a rectilinear path transverse of the axis of rotation of said holder.

15. In an edge setting machine, in combination, a supporting member, a tool holder rotatably mounted thereon, means for locking said holder against rotation, and a single 85 member engageable by the hand of the operator, and movable in a rectilinear path for disengaging said locking means.

16. In an edge setting machine, in combination, a frame member, a rocker arm pivoted to vibrate thereon, a tool holder 95 rotatably mounted upon said rocker arm, and a single, manually operable member slidable in a path transverse of the axis of rotation of said holder and constructed and arranged to cause rotational movement of 100 the latter.

17. In an edge setting machine, in combination, a supporting member, a tool holder rotatably mounted thereon, means for locking said tool holder against rotation, means 105 engageable with said holder for turning the same, and a single reciprocal element constructed and arranged to render inoperative said locking means when moved in one direction, and to actuate said turning means 110 when moved in the opposite direction.

18. In an edge setting machine, in combination, a rotatably mounted tool holder, means for locking said tool holder against rotation, and means for unlocking and turning 115 said holder comprising a slide member, a spring for moving said member in one direction, and a manually engageable element for moving said member in the opposite direction.

19. In an edge setting machine, in combination, a rotatably mounted tool holder, means for locking said tool holder against rotation, positively acting means for unlocking said tool holder to permit rotation 125 thereof, and resilient means for rotating said holder.

20. In an edge setting machine, in combination, a rocker arm, a tool holder rotatably mounted thereon and provided with one ele- 130

ment of a ratchet clutch, a coöperating clutch element relatively movable into and out of engagement with said first element, resilient means normally acting to retain 5 said elements in driving engagement, and means for alternately rotating said second clutch element in opposite directions, said elements being constructed and arranged to be disengaged upon rotation of said first 10 element in one direction.

21. In combination in a machine of the class described, a rocker arm having a journal opening therein, a tool holder having a pintle journaled in said opening, a clutch 15 element rotatable with said tool holder, a coöperating clutch element slidable in said arm and resiliently urged toward said first element, a gear fast to said second clutch element, a rack engageable with said gear, 20 and means whereby said rack may be reciprocated.

22. In an edge setting machine a supporting frame, a rocker arm pivoted thereto, means for vibrating said arm about its pivot, 25 a tool holder rotatably mounted upon said arm, means for locking said tool holder in either of a plurality of operative positions, means for disengaging said locking means, means for rotating said tool holder, a member freely slidable within said rocker arm, 30 a spring located within an opening in said frame and engaging one end of said member, a knob upon the opposite end of said member, and means carried by said member for actuating said lock disengaging and said turning means.

23. In an edge setting machine, a tool supporting member, a tool holder rotatably mounted with respect thereto, the opposed, 40 adjacent surfaces of said parts being maintained in constant contact, a spring-projected locking pin slidably guided in one of said parts and constructed and arranged to engage an opening in the other of said 45 parts to lock them against relative rotation,

means for disengaging said pin from said opening to permit rotation of one of said parts with respect to the other, and means for relatively rotating said parts, the surface of that part provided with the opening 50 having formed therein an inclined groove leading into said opening for insuring reengagement of the locking pin therewith.

24. In an edge setting machine, in combination, a rocker arm, a tool holder rotatably mounted thereon, latch means carried by one of said parts for locking said parts against relative rotation, and means carried by the other of said parts for rendering said latch means inoperative. 55

25. In an edge setting machine, in combination, a rocker arm, a tool holder rotatably mounted thereon, latch means carried by said tool holder for locking said parts against relative rotation, and means carried 60 by said rocker arm for rendering said latch means inoperative.

26. In an edge setting machine, a rocker arm, a tool holder rotatably mounted thereon, latch means carried by one of said parts 70 for locking said parts against relative rotation, and means carried by the other of said parts for rendering said latch means inoperative both of said means being located 75 wholly within the periphery of said parts whereby they are protected from injury.

27. In an edge setting machine, a rocker arm, a tool holder rotatably mounted thereon, latch means carried by one of said parts for locking said parts against relative rotation, releasing means carried by the other of said parts for rendering said latch means inoperative both of said means being located wholly within the periphery of said parts 80 whereby they are protected from injury, and means extending without said parts for actuating said latch-releasing means. 85

In testimony whereof, I have signed my name to this specification.

OTIS R. ANGELL.
